UNITED STATES PATENT OFFICE.

ELMER B. BIRD, OF LITTLE ROCK, ARKANSAS.

PRODUCING GASOLINE FROM NATURAL GASES.

Application filed March 19, 1927. Serial No. 176,827.

The present invention contemplates production of low boiling hydrocarbons, such as gasoline, from permanent gases, such as are usually to be obtained from oil and gas wells, or other sources.

It has been found that when, for example, natural gases are treated in accordance with my process, that gasoline of excellent quality may be produced.

10 The invention consists in utilizing natural gas or other hydrocarbon vapors, and pre-heating such gas up to a temperature of approximately 500° C., depending, of course, upon the particular gas being utilized.

15 Thereafter, the heated gas is passed through a tube or battery of tubes containing catalytic material.

The tubes in question may be of metal or glass, or any suitable piping, as may be found 20 most convenient. Disposed within the catalytic tube are the materials which exert a beneficial action upon the heated gas. It may be stated here, that the gas, when it is supplied to the catalytic tube, possesses a

25 temperature below 500° C., and I have found in my experiments that the process can be carried out with great efficiency if the gas is between 200° C. and 400° C. when it leaves the outlet of the treating chamber, the temperature varying with the rapidity of expansion of the treated gas as it discharges. In other words, the gas in the treating chamber has a temperature between 400° C. and 500° C. and as it leaves the chamber, the temperature of the treated gas falls in accordance 35 with the rapidity of expansion of the gas.

At this point, it should also be explained that ordinarily no pressure is applied mechanically to the fluid in order to propel it, 40 but if the gas pressure is not sufficient, an appropriate booster pump may be utilized to force it through the apparatus.

The catalytic material consists of asbestos fibres, or other porous materials, which are 45 saturated with solutions of the common metals, such as nickel and copper nitrate, and which have also been treated with salts of noble metals, such as the chlorides of gold, platinum and palladium. The catalyzer is 50 retained in position in the treating chamber by means of a series of spaced screens to which it may be attached and which serve to maintain the material in the path of the gas, so that the gas will pass through a maximum 55 amount of the catalyzer.

It will be understood, of course, that hydro-

gen is passed through the tube in order to reduce the metals, and it is further desirable to pass an inert gas, such as carbon dioxide, nitrogen, or steam, over the reduced material 60 to free it of any hydrogen which has found its way into the porous catalyzer.

It is found that the catalytic material so deposited and treated, is substantially a mixture of the common and nobler metals. 65

It is quite desirable, with some natural gases, at times to incorporate with the gas under treatment, approximately 5% of acetylene, since this has a very beneficial effect. This percentage would be varied slightly 70 for different gases. The acetylene gas is usually independently heated to a temperature of approximately 400° C., but, may be of course, heated along with the gas under treatment, if desired. 75

The acetylene under heat will polymerize to benzine, which has a very beneficial effect on the process, enabling the liquid product to be readily formed, and also increasing the 80 yield of gasoline.

The gas which is emitted from the catalyzer tubes is passed to a condensing apparatus of any suitable character, and the condensed fluid is drawn off to a suitable storage container. 85

After passing through the treating plant, some dry gas will be catalyzed to wet gas, but not sufficiently catalyzed to liquefy in the condenser. This wet gas may be removed by compression or absorption, for the purpose of making natural gasoline. The waste gas from this latter treatment may be used as fuel or returned to the system for treatment. 90

This process is probably best carried out 95 with the gas obtained from natural gas wells, and it is immaterial whether the gas be wet or dry gas.

The yield of high test gasoline is exceptional, and the process is speedy and obviously simple, requiring no pressure and relatively low temperature, and practically any type of apparatus having the requirements explained may be set up and utilized. 100

The figure is a diagrammatic flow sheet 105 of one type of apparatus for carrying out the invention.

In the drawing appended hereto, the numeral A indicates a gas-well having a suitable pipe communicating with a preheater B. The heated gas is then passed to a chamber containing the catalytic material indi- 110

ated at C. From the catalytic chamber, the treated gas is passed to a condenser D, and thence into the storage receptacle E. Uncondensed gas collecting in the storage receptacle may escape to a compressor, or absorption plant F, and any gas not liquefied by this apparatus may be returned to the system through the pipe G. The letters H and I indicate temperature indicating means such as thermometers, the thermometer H registering the temperature of the treating chamber and the thermometer I registering the temperature of the gases which discharge from said treating chamber.

15 What is claimed as new is:—

1. The process of preparing low boiling liquid hydrocarbons which comprises subjecting a mixture of natural gas and a small proportion of acetylene to intimate contact with a porous catalytic agent of common and nobler catalytic metals without mechanical pressure, and between a temperature of 400° C. and 500° C. to produce hydrocarbons which are recovered in liquid form.

2. The process of preparing low boiling liquid hydrocarbons which comprises sub-

jecting natural gas to intimate contact with a porous catalytic agent of common and nobler catalytic metals without mechanical pressure, and at a temperature between 400° 30 C. and 500° C. to produce hydrocarbons which are recovered in liquid form.

3. The process of preparing low boiling liquid hydrocarbons which comprises subjecting natural gas to preheating, and passing the gas through a porous catalytic agent comprising common and nobler catalytic metals without mechanical pressure and at a temperature between 400° C. and 500° C. 35 to produce hydrocarbons which are recovered in liquid form.

4. The process of preparing low boiling liquid hydrocarbons which comprises preheating a mixture of natural gas and a small proportion of acetylene, passing the preheated mixture through a porous catalytic agent comprising common and nobler catalytic metals without mechanical pressure, and at a temperature between 400° C. and 500° C. 40 to produce hydrocarbons which are recovered in liquid form.
